FRAME

Joseph Alfred Schuck, Bound Brook, N. J.

Application August 18, 1938, Serial No. 225,543

7 Claims. (Cl. 40—152.1)

This invention relates to a frame, which serves as a support holder and stand for flat objects to be exhibited, such as tablets, boards, mounted pictorial presentations or legends, which may for instance be assembled with a protective and reinforcing transparent plate or sheet, such as glass. Such an object will hereinafter be defined as a stiff sheet object.

The general object of this invention is to provide a frame, which may be readily, replaceably and at random applied to a stiff sheet object of any size, and will thus facilitate the setting up or hanging of the object onto a suitable support, i. e. a level, inclined, or upright structure, such as a table wall or column.

Other objects of this invention, which are mostly incidental to the general object just stated, will be elucidated in, and better understood from the following exemplary description of the invention. The description together with the accompanying drawing should be interpreted as illustrative rather than in limitation of this invention.

In the drawing:

Fig. 1 shows a perspective view of a device of this invention which is applied to and supports a flat sheet object.

Fig. 2 is a detailed view showing a cross-section taken at a level and in a direction pointed out in Fig. 1 by a dot-dash line, an arrow and the numeral 2.

Fig. 3 is another detailed cross-section, the direction and level of which is pointed out by a dot-dash line and an arrow and the numeral 3 in Fig. 1.

Fig. 4 is a sectional plan view of a sheet which may be used supplemental to a frame of this invention.

Fig. 5 is a sectional, developed view of another supplemental sheet made of rubber or like material.

Fig. 6 is a sectional view of a supplemental sheet which is modified as compared with the embodiment of Fig. 5.

Fig. 7 is a horizontal cross-section of a plug supplemental to a frame of this invention.

Fig. 8 shows a corresponding vertical cross-section.

Fig. 9 shows an elevation of sheeting used in connection with the device just referred to.

Fig. 10 is a corresponding top view.

Similar numerals refer to similar parts throughout the various views.

Unless some readily available auxiliary means are used, a device of this invention does not serve to support a limp object structurally in its plane. In this respect a device of this invention differs from the ordinary frame, which usually surrounds a sheet object completely, thereby normally also supporting it in its plane. The sheet

object referred to is therefore generally defined as a stiff sheet object, it being understood that a limp sheet object may readily be converted into a stiff sheet object by a suitable backing or covering.

A device of this invention comprises a pair of brackets, which may be substantially aligned. But, for purposes of economy of material and still providing a maximum structural strength and stability, the brackets may be made symmetrical to each other, i. e., there is a right bracket 11, and a left bracket 12. This arrangement will also effect a certain harmony of the appearance; although appearance is not emphasized herein. 15 It is understood, that the appearance of a device of this invention may be vastly improved upon; but this specification is limited to the simplest details required for an embodiment of this invention.

10 Each of the brackets comprises a riser 13 and a leg 14, which in the drawing is shown as complementary half-round sections, rounded off at opposite ends, and pivotally pressed together by a screw 15 at a fulcrum joint. Thus they are frictionally engaged upon each other, and the riser and leg may be swung into alignment, when they represent a substantially round cross-section. However the leg 14 does not necessarily have to be as long as the riser 13.

25 It is desirable to have such frictional contact between the riser 13 and the leg 14, that they are fairly stable at any setting, when a stiff sheet object is mounted therein and supported thereby. Thus frictional contact between the riser and the leg may be improved upon, by providing additional securing means at the fulcrum point, or by providing a spring or spring washer 16 underneath the head of the screw 15, which is shown in Fig. 3 as a shoulder screw.

20 A stiff sheet object is indicated in the drawing as a commonly used embodiment, i. e. one or more pictorial representations 17 engaged between a pair of glass plates 18 and 19. A longitudinal slot 20 divides the upper portion of the riser 13 into bifurcations or forks 21 and 22, and is of such width that it accommodates a stiff sheet object of an average thickness, together with some spacing or gripping means, which will be presently explained.

25 Means ought to be provided which clamp together the forked ends 21 and 22, produced in the riser 13 by the slots 20. According to the drawing, one or more thumb screws 23 and 24 may be provided for such purpose. Such screws are offset to one side, i. e. they extend through the end 21 near the lateral outer surface thereof, and into the other end 22, where they are threadedly engaged. The stiff sheet object is inserted in the slot 20 together with spacers or elastic sheeting, so that the width of the slot 20 is sub-

stantially filled, and then the ends 21 and 22 are clamped together by manipulation of the screws 23 and 24, this operation being repeated in connection with the left bracket 12, after it has been performed in connection with the right bracket 11. The slot 20 may be flared out wider for a certain distance near its outer end, as indicated at 26, so that the stiff sheet object is firmly retained in slots 20, rather than being squeezed out thereof.

When spacing sheets 27 are used, they are preferably notched in order to clear the tensioning means such as screws 23 and 24, and so that one or more of these spacers may be inserted at random, each spacer being for instance made out of cardboard.

A firmer engagement of the stiff sheet object 25, particularly when it is wide and possibly also extends high above the riser 13, may be procured by using a folded frictional, e. g. rubber sheet 28, which is provided with a plurality of perforations 29, near the center line, these perforations fitting over the shanks of the thumb screws 23 and 24. If the spacers 28 are made out of rubber, but are fairly stiff, they will always spread apart in order to allow ready insertion of a stiff sheet object 25.

But in place of these perforations 29, the elastic sheet 28 may also contain slots 30, which correspond to the notches of the spacer 21, so that the folded sheet 28 may be placed over the edge of the stiff sheet object 25, before it is inserted into a slot 20. Risers 13, and legs 14 are exemplarily indicated in the drawing as being made of wood, but any other material of suitable resiliency, such as metal or molded material, may be used and shaped as fancy and fashion may dictate. The riser 13, should of course be of such width, that it liberally engages upon the margin of a stiff sheet object alongside of the clamping means such as thumb screws 23 and 24. And it should be of such cross-section that it is not readily twisted when the forks 21 and 22 are pulled together for clamping purposes.

When the stiff sheet object 25 is assembled from a plurality of sheets, it might gape along an outside margin, when clampedly engaged along the lower sides by the brackets 11 and 12. Then it may be advisable to use suitable plugs 31 for the corners and 32 for the upper edge in connection with the brackets 11 and 12. Such lugs 31 and 32 may be slotted angularly or across respectively, preferably with bevelled entrance corners, such as indicated at 33 in connection with the slot 34 in the spherically shaped lugs 31. The slots 34 may be gouged so as to be wider at their bottoms. This is particularly helpful in connection with spacers or molded rubber formations 35, which serve to fill the slot when it is too wide for the thickness of the stiff sheet object 25, such spacers 35 lodging in the widened bottom portion of the slot 34, so that they do not readily slide off an assembled stiff sheet object 25.

A frame of this invention may also be placed flat against a support, when the riser and leg are swung into alignment with each other. Then the frame may for instance be, the drawing showing for such purpose underneath screws 23, a washer 36 with an extension perforated (37) to engage a string or hook.

Having thus described this invention in detail, yet I do not wish to be limited thereby, except as the state of the art and the appended claims may require, for it is obvious that various modi-

fications and changes may be made in the form of embodiment of my invention, without departing from the spirit and scope thereof.

What I claim is:

5. 1. A frame comprising a pair of brackets, each of said brackets including a riser having forked ends separated by a slot of a width suitable to receive a marginal portion of a stiff sheet object, and having clamping means on one side of said ends for pulling them together into clamped abutment with an object placed into said slot.
10. 2. A frame comprising a pair of symmetrically arranged risers which are slotted from the top down but short of their lower ends, screws offset to one side on said risers and serving to pull the upper ends of said risers together across said slots, in order to clamp upon a stiff sheet-like object inserted on its opposite sides into said slots, said risers being relatively spaced and secured in a common plane by such an object, and a support extending from one of said risers in a plane substantially normal to said common plane and adapted to be set at a preferred angle in said normal plane.
15. 20. 3. A frame comprising a pair of risers bifurcated for a major portion of their length, clamping means interconnecting the bifurcations of each riser on one side, so that opposite sides of a stiff, sheet-like object to be framed may be inserted and engaged between the bifurcations of each riser from the other side of said riser, said risers being relatively spaced and secured in a common plane by such an object, and a support extending from one of said risers in a plane substantially normal to said common plane and adapted to be set at a preferred angle in said normal plane.
25. 30. 4. A frame comprising a pair of risers bifurcated for a major portion of their length, the bifurcations of each riser being farther apart upon one side than on the other, and screw means interconnecting the bifurcations of each riser on the farther apart side, so that an object to be framed may be inserted between the bifurcations of each riser from the opposite side thereof where the bifurcations are closer together.
40. 45. 5. A frame comprising a pair of brackets, each of said brackets including a bifurcated riser, contracting means for clamping said bifurcations side ways onto a stiff sheet object inserted therebetween, and a leg clampedly fulcrumed onto said riser so that said riser and leg may be set at random at a preferred angle with each other, at which the risers and an object clampedly engaged thereby are to be supported on a supporting surface.
50. 55. 6. A frame comprising a pair of brackets, each of said brackets including a bifurcated riser, screws for clamping said bifurcations onto a stiff sheet object inserted therebetween, and a folded sheet of elastic material perforated on opposite sides of the fold in order to receive said screws and shaped to fit between said bifurcations over an object inserted between said bifurcations.
60. 65. 7. A frame comprising a pair of brackets, each of said brackets including a bifurcated riser, screws for clamping said bifurcations onto a stiff sheet object inserted therebetween, and a folded sheet of elastic material slotted towards opposite sides from the fold in order to receive said screws and shaped to fit between said bifurcations over an object inserted between said bifurcations.

JOSEPH A. SCHUCK.
